Patented Feb. 2, 1915.

UNITED STATES PATENT OFFICE.

DANIEL KOPS, OF NEW YORK, N. Y.

APPAREL-CORSET.

1,127,023.

Specification of Letters Patent.

Patented Feb. 2, 1915.

Application filed September 12, 1914. Serial No. 861,349.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

In Letters Patent, No. 1,082,273, granted to me December 23, 1913, for apparel corsets, there is shown and described a garment comprising corset body halves, skirts depending therefrom and extending from the rear medial line of the corset forwardly, and front skirt extensions, each completing the continuity of the skirt section depending from one corset body half and secured thereto along one edge and also along the upper edge an appreciable distance from the lower front edge of the corresponding corset body half. The construction of this corset is such that the front skirt sections overlie a portion of the lower front of the corset body, so that the latter may be adjusted to properly fit and support the abdomen of the wearer. In the adjustment of the garment, however, due to the fact that the front skirt sections are attached to the corset body, the tendency, in use, is to wrinkle the garment in the lower front portions thereof. To overcome this difficulty, and as shown and described in Letters Patent No. 1,105,330, granted to me July 28, 1914, a garment has been made in which the front skirt sections, at their upper edge, are free from the corset body and are adjustably attached thereto, the principal objects of both constructions being to complete the continuity of the skirts to properly confine the hip sections of the body and to adequately support the abdomen of the wearer independently of the skirts. It is to be noted, however, that in the latter named patent, the adjacent parallel edges of the front skirt sections are more or less separated, depending upon the adjustment of the garment, and hence the continuity of the skirt, strictly speaking, is not complete from the rear to the front medial lines thereof.

The object of my present invention is therefore to overcome this difficulty, as well as that of the wrinkling of the skirt sections at the lower front portions of the garment, and to, at the same time, afford adequate support for the abdomen of the wearer, and furthermore, in the garment made in ac-

cordance with my present invention, the construction is such that in effecting the abdominal support, by forcing the lower front portions of the corset body proper to bear against the body of the wearer, the pressure exerted also forces the garment outwardly below the bust sections thereof, so as to produce the bridge effect which is obtained in various other corsets for which patents have heretofore been granted to me.

In carrying out my present invention, the garment preferably comprises corset body halves, skirts depending therefrom and extending from the rear medial lines forwardly, a front skirt section completing the continuity of the skirt in each corset body half and attached to its skirt along one side edge and to the corset body an appreciable distance above the front lower edge thereof, each skirt section forming a downwardly continuation of a portion of the body of the corset, and which, along its front edge, overlies the lower front portion of the corset body half, tension straps secured at one end to the corset body half distant from the front edge thereof, means for connecting the free ends of the tension straps at the lower front portion of the corset body half, to adjust the same in place, a front flap connected at its upper edge to the lower front portion of the corset body half on the same or substantially the same line as that at which the skirt section is connected thereto, and hose supporters secured to and extending from the lower edges of the said flaps and skirt extensions. The position of the depending flaps is permanent and completes the continuity of the skirts at the front thereof, while the underlying front portions of the skirt sections are adjustable to position beneath the depending flaps, depending upon the position of the tension straps, so that the continuity of the skirt sections of the garment is complete and has no tendency to wrinkle. The front skirt sections are adjustable to position with their front edges lying beneath the depending flaps, both of which are independent of the lower front portion of the garment, so that by the tension applied to the hose supporters inward pressure is exerted to bear against the abdomen of the wearer to properly support the same, at the same time the upper front sections of the garment, beneath the bust line, are forced outwardly to produce the bridge effect and relieve any

possible pressure against the diaphragm of the wearer, as will be hereinafter more particularly described.

In the drawing, Figure 1 is a front elevation, on a small scale, of an apparel corset embodying the features of my present invention. Fig. 2 is an elevation of the lower front portion of one of the corset body halves showing the parts thereof broken 10 away to more clearly illustrate the construction, and Fig. 3 is an edge elevation of the parts of the garment as illustrated in Fig. 2.

Referring to the drawing, my improved apparel corset comprises corset body halves 15 10—11, which, as usual, are provided along their front edges with the customary steels 12, so as to be united by stud and socket members forming part thereof. At the rear, the corset body halves are provided 20 with eyelets, in order that the usual laces 13 may be employed, and in suitable positions the body of the corset is fitted with boning, indicated at 14.

The corset body half 10 has a depending 25 skirt 15 extending from the rear medial line forwardly, and similarly the corset body half 11 has a depending skirt 16 extending from the rear medial line forwardly. Substantially completing the continuity of the 30 depending skirts 15 and 16 are front skirt sections 17 and 18. These skirt sections are similar but reversed in the halves of the garment, and for this reason but one of them will be hereinafter described.

Referring particularly to Fig. 2, the front skirt section 17, as will be seen, is a substantial continuation of that portion 19 of the front of the corset body half 10. At one side edge, the skirt extension 17 is secured to 35 the depending skirt 15 along the side 20, and along a portion of its upper edge, the skirt section 17 is secured to the front lower portion of the corset body half on a line 21, which is a substantial distance above the 40 front edge of the corset body. As clearly indicated in this figure of the drawing, the front edge of the skirt section 17 preferably tapers, as indicated at 22, from the lower front corner thereof to the line of attachment to the corset body half. I also employ an overlying depending flap member 23. At its upper edge, each flap member is connected to the lower front portion of the corset body half on the same line 21 by which the underlying 45 upper edge of the skirt section 17 is connected thereto. The flap member 23 extends downwardly from its line of attachment to the corset body half, overlying the front edge of the skirt section 17, and terminating 50 at the lower edge of the skirt section 17, adjacent the front thereof, to both of which members, at this point, a hose supporter 24 is suitably attached. I also employ in each 55 corset body half a series of tension straps 60 25. These tension straps, in spaced posi-

tions, are secured to the corset body half along a line distant from the front edge thereof, and preferably converge to their other ends where they are suitably united and provided with eyelets 26, each of which 70 is adapted to engage a hook or stud 27 provided on the lower portion of the corresponding corset steel. As will be apparent, the pressure exerted by the lower portion of the corset body against the abdomen of the 75 wearer may be adjusted by the position of the tension straps 25, that is to say, by passing the hook 27 through the outer or the more inwardly located eyelets 26, and that irrespective of the pressure applied to the 80 body of the wearer by the lower front portion of the corset body the independently overlying skirt portions properly confine the hip and upper limb sections of the 85 wearer.

It is to be noted that in this garment the tension straps 25, from the point of their attachment to the body portion of the corset to the point where they pass over the lower portion thereof, lie directly against the inner surface of the garment, and consequently directly against the clothing worn beneath the corset, while at their joined ends the tension straps overlie the lower front portions of the corset body.

From the foregoing it will be apparent that inasmuch as the skirt sections 17 and 18 are substantially downward continuations of the corset body, they will assume their proper positions, in use, without wrinkling, irrespective of the adjustment of the tension straps, and that irrespective of their positions, the front edges thereof lie beneath the depending flaps 23, and hence the continuity of the skirt section is complete without reference to the position of the front skirt sections 17 and 18. Also that by the tension applied by the hose supporter 24, as well as that exerted by the tension straps, the lower front portions of the 105 corset will be forced inwardly against the abdomen of the wearer to adequately support the same, and that the upper front portion of the corset below the bust line will be forced outwardly to obviate any 110 pressure which would otherwise be exerted against the diaphragm.

In the corset as hereinbefore described, each front skirt section, as stated herein, is a continuation of the front portion of the 120 corresponding corset body half. Also each flap member 23 is a continuation downwardly of the member 28, forming the immediate front portion of each corset body half, with part of each corset body half at 125 the lower front extremity thereof being formed by a separate member 29, which extends from the lower extremities of the corset steels to the line 21, at which it is connected to the front skirt sections and 130

the flap members, by which line, as hereinbefore stated, these members are also connected together.

I claim as my invention—

- 5 1. In an apparel corset comprising corset body halves, each having a depending skirt extending from the rear medial line thereof forwardly, front skirt sections substantially completing the continuity of said depending skirts from the rear to the front medial lines 10 of the corset, each skirt section being secured along one side edge to its skirt and also to the corresponding corset body half on a line appreciably above the lower front edge thereof, front flap members each connected at its upper edge to the lower front portion of the corset body half on a line a substantial distance from the lower edge thereof, and tension devices, the said front 15 flap members overlying the corresponding skirt sections and being free therefrom except at the lower edges to which the said tension devices are secured.

2. In an apparel corset comprising corset body halves, each having a depending skirt extending from the rear medial line thereof forwardly, front skirt sections substantially 25

completing the continuity of said depending skirts from the rear to the front medial lines of the corset, each skirt section being 30 secured along one side edge to its skirt and also to the corresponding corset body half on a line appreciably above the lower front edge thereof, a series of tension straps secured at their distant edges to the corset 35 body and adjustable to position at the lower front edge of each corset body half, front flap members each connected at its upper edge to the lower front portion of the corset body half on the same line to which the said 40 front skirt sections are secured, hose supporters, each said front flap member overlying the front portion of the corresponding skirt section and being free therefrom except at the lower edges where they are 45 connected and one of the said hose supporters is secured.

Signed by me this 4th day of September, 1914.

DANIEL KOPS.
